CHESTER ARTHUR PURDY, OF OAK PARK, ILLINOIS, ASSIGNOR TO WESTERN ELECTRIC COMPANY, INC., OF NEW YORK, N. Y., A CORPORATION OF NEW YORK

METHOD OF AND APPARATUS FOR PREPARING COMPOUNDS

Application filed February 29, 1928. Serial No. 258,123.

This invention relates to a method of and apparatus for preparing compounds, and more particularly to a method of and apparatus for preparing insulating compounds.

It is the practice in some instances to impregnate electrical coils composed of insulated conductors with a protective covering of insulating material. Thus, certain types of electrical coils such as loading coils of the type employed in telephone systems are usually impregnated with an insulating covering consisting of rosin and rosin oil compound. This compound has heretofore been prepared in some instances by heating and occasionally stirring the lump rosin and the rosin oil in a suitable tank over a long period of time, usually more than forty-eight (48) hours. This method is obviously very slow and expensive and requires a high degree of skill as well as very close attention in order to insure a thorough mixing and drying of the compound which is essential to secure the desired electrical characteristics.

The principal object of the present invention is to provide an improved and inexpensive method of and apparatus for expeditiously and efficiently preparing and treating compounds.

In accordance with the invention, an improved method of preparing compounds consists in heating the raw ingredients to a predetermined temperature, simultaneously mixing the heated ingredients by continuously circulating them between a plurality of heated tanks, and drying the resulting compound or mixture by subjecting it to a vacuum.

The present invention may be employed to particular advantage in the preparation of rosin and rosin oil compounds used for insulating electrical coils. In accordance with this embodiment of the invention, suitable quantities of the raw ingredients consisting of rosin and rosin oil are deposited in a heated tank filled with previously prepared compound, the compound thus displaced passing through a suitable strainer into a second heated tank. As additional

amounts of raw ingredients are deposited into the first tank, equivalent amounts of the heated compound are displaced into the second tank and simultaneously therewith a continuous circulation of the compound is maintained between the two tanks so as to thoroughly mix the ingredients. When the second tank is filled with the heated and thoroughly mixed compound, a vacuum is applied to the entire system to thoroughly dry the compound. The compound thus treated is then stored in a suitable reserve tank from which it may be drawn as desired.

It is believed that the invention will be clearly understood from the following detailed description of a specific embodiment thereof, reference being had to the accompanying drawing which schematically illustrates an apparatus embodying the invention and which may be employed in practicing the improved method in preparing an insulating compound consisting of rosin and rosin oil. It is to be understood, however, that the invention is not limited to the specific method or apparatus disclosed except as defined in the appended claims.

Referring to the accompanying drawing, an apparatus embodying the features of the invention comprises a pair of tanks 10 and 11 of any suitable construction and supported upon vertical standards 12 and 13, respectively. The tanks 10 and 11 are interconnected near the upper portions thereof by means of a horizontal pipe or conduit 14, one end of which protrudes into the tank 10 and terminates in a suitable strainer or filter 15. The material to be treated is deposited into the tank 10 through a filling door 16 provided at the top thereof.

A conduit 17 extending from the top of the tank 11 is connected to a suitable vacuum pump (not shown). Vertically disposed conduits 18 and 19 extending from the tops of the tanks 10 and 11, respectively, are connected to a horizontally disposed conduit 20 which in turn is connected to a two-way air valve 21. The air valve 21 is connected to a suitable source of compressed air (not shown) by means of a conduit 22. Horizontally disposed conduits 23 and 24 extending

from the bottoms of the tanks 10 and 11, respectively, are interconnected by a two-way valve 25. A pipe 26 leading from the valve 25 terminates within a third tank or blow case 28 which is positioned below the tanks 10 and 11 and is substantially smaller than them. A vertically disposed conduit 30 extending upwardly from the top of the blow case 28 is connected to the air valve 21.

5 Pivotally supported upon a bracket 32 secured to the top of the blow case 28 is an L-shaped member 33. A pair of mercury contact switches 34 and 35 of any suitable type comprising a sealed tube housing a pair of spaced electrodes and a body of mercury are carried by a vertical arm 36 of the pivoted member 33. The contact switches 34 and 35 are disposed in opposed relation to each other so that when one is closed the other is open and vice versa. A horizontal arm 38 of the member 33 is pivotally connected at its end to a vertically disposed rod 40 which is slideable in the top or cover of the blow case 28 and extends approximately to the bottom thereof. Slidable on the rod 40 between a pair of spaced stop collars 41 and 42 is a block 43 composed of any suitable material adapted to float in the compound being prepared.

10 One contact terminal 45 of the mercury switch 34 is connected to one end of the winding of a solenoid 46 through a conductor 47. A contact terminal 48 of the mercury switch 35 is similarly connected to one end of the winding of a solenoid 50 through a conductor 51. The opposite ends of both solenoid windings are connected to a line conductor 52 and the other terminals 53 and 54 of the switches 34 and 35, respectively, are connected to a line conductor 55. The line conductors 52 and 55 are connected to a suitable source of electrical energy (not shown).

15 As shown in the drawing, the solenoids 46 and 50 may be mounted in a common supporting frame 57 which may be supported in any suitable manner. Pivotally supported intermediate its ends in a bracket 58 secured to the solenoid frame 57 is a horizontally disposed bar 60 which is pivotally connected on opposite sides of its pivot to cores 61 and 62 of the solenoids 46 and 50, respectively. One end of the bar 60 is connected to an operating lever 63 of the air valve 21 by means of a link 64 while the opposite end of the bar 60 is connected to an operating lever 65 of the valve 25 by means of a link 66.

20 Mounted within the tanks 10, 11 and 28 are spiral steam pipes 68, 69 and 70, respectively, which may be connected in any suitable manner to a steam line so that the compound is constantly maintained at a predetermined temperature.

25 The operation of the above described ap-

paratus is as follows: Assuming that upon starting the operation of the apparatus the tanks 10, 11 and 28 are empty, then it will be obvious that the float 43 will have dropped to the lower stop 42 on the rod 40 and will have caused the rod 40 to move downwardly whereby the pivoted member 33 is turned in a clockwise direction thus closing the contact switch 34 and opening the contact switch 35. As will be clearly understood by referring to the drawing, the closing of the contact switch 34 establishes an electrical circuit through the winding of the solenoid 46 and the opening of the contact switch 35 opens a previously established circuit through the winding of the solenoid 50. The solenoid 50 is thereby de-energized whereupon the energization of the solenoid 46 causes the latter to retract its core 61, thus turning the pivoted bar 60 in a clockwise direction. This movement of the bar 60 causes an upward movement of the link 66 and a downward movement of the link 64, thus turning the valve operating levers 65 and 63 in a clockwise and counter-clockwise direction, respectively, to the positions shown in full lines in the drawing. When so positioned, the two-way valve 25 opens the passage between the tank 11 and the blow case 28 and closes the passage between the tank 10 and the blow case, while the two-way air valve 21 opens the air passage between the tanks 10 and 11 and the blow case 28 and closes the passage between the compressed air line 22 and the blow case.

30 After the valves 21 and 25 have been set as described above, the tank 10 is filled up to the strainer 15 preferably with previously prepared compound. If this amount of prepared compound is not available the required quantities of the rosin and rosin oil ingredients are deposited into the tank 10 wherein they are thoroughly mixed and heated as has been the practice heretofore. In other words, it is to be understood that the outstanding advantages of the improved system and apparatus are particularly effective when the tank 10 has been filled with the thoroughly heated and prepared compound.

35 Upon the tank 10 being filled with the thoroughly treated compound, additional quantities of the ingredients consisting of lump rosin and rosin oil are deposited therein, thus displacing a portion of the prepared compound. The displaced compound passes through the strainer 15 and conduit 14 into the tank 11 from which it passes through the conduit 24 into the blow case 28. As additional quantities of the ingredients are deposited into the tank 10, additional amounts of the prepared compound pass into the blow case 28 and as the level of the compound in the blow case rises, the float 43 moves upwardly along the rod

40 until it strikes the upper stop 41 moving the rod 40 upwardly and thereby turning the pivoted member 33 in a counter-clockwise direction. This movement of the member 33 closes the contact switch 35 and opens the contact switch 34 thus opening the previously established circuit through the winding of the solenoid 46 and closing the circuit through the winding of the solenoid 50. The solenoid 46 is thereby de-energized whereupon the energization of the solenoid 50 causes the latter to retract its core 62 thus turning the bar 60 in a counter-clockwise direction. This movement of the bar 60 reverses the valves 21 and 25, as shown in dotted outline in the drawing. The air valve 21 now closes the air passage between the blow case 28 and the tanks 10 and 11 and opens the passage between compressed air line 22 and the blow case 28; and the valve 25 opens the passage between the tank 10 and the blow case and closes the passage between the blow case and the tank 11. The compressed air entering the blow case through the top thereof forces the compound through the pipe 26, valve 25 and conduit 23 into the tank 10 through the bottom thereof. As the blow case empties, the float 43 moves downwardly along the rod 40 and upon striking the lower stop 42 the rod 40 is moved downwardly again reversing the valves 21 and 25 in the manner hereinbefore described. Meanwhile, the compound is constantly maintained at a predetermined temperature by the steam pipes 68, 69 and 70.

Additional quantities of the ingredients are deposited into the tank and the above described cycle of operation is repeated until tanks 10 and 11 are both filled with the thoroughly mixed and heated compound, after which the filling door 16 is closed and a vacuum is applied to the entire system through the conduit 17, the circulation of the compound between the tanks 10 and 11 and the blow case 28 continuing in the manner described above until the compound is thoroughly dried. When thoroughly treated the compound may be transferred from the tank 11 into a suitable reserve tank wherein it is stored until required for use.

By the application of the present invention as described above, it has been found that an improved compound is produced at a substantial saving of time and expense. The forced circulation between the tanks 10 and 11 and the blow case 28 insures a thorough mixing of the ingredients. Furthermore, the use of a vacuum not only insures a thorough boiling off of the moisture but also provides a means for removing the vapors produced thereby.

Although the invention is herein illus-

trated and described in connection with the preparation of an insulating compound consisting of rosin and rosin oil, it is to be understood that the novel features thereof are capable of other applications within the scope of the appended claims.

What is claimed is:

1. A method of preparing rosin-rosin oil insulating composition, which consists in adding to a container containing a quantity of liquefied material solid ingredients of the material, liquefying the solid ingredients, allowing said liquefied material to flow continuously into a second container from which it flows to another container, automatically interrupting the flow of liquefied material into the last mentioned container, causing the material in said last container to be returned to the original liquefied material while the flow of the material continues from the first to the second container, and withdrawing the material from the second container after liquefaction of the materials.

2. Apparatus for preparing insulating compositions including a pair of tanks, one of which is arranged to receive materials to be liquefied, a connection between said tanks through which liquefied material flows upon being displaced due to the addition of solid ingredients to the first tank, a third tank of smaller dimensions than the other tanks connected with the two tanks, means in the third tank responsive to the flow of material from one of the other tanks, and an electrical means operated when a predetermined amount of liquefied material flows into said third tank for causing the liquefied material therein to be returned to the larger tank into which the solid ingredients are placed.

3. Apparatus for preparing insulating compositions including a pair of tanks, one of which is arranged to receive materials to be liquefied, a connection between said tanks through which liquefied material flows upon being displaced due to the addition of solid ingredients to the first tank, a third tank of smaller dimensions than the other tanks connected with the two tanks, means in the third tank responsive to the flow of material from one of the other tanks, electrical means operated when a predetermined amount of liquefied material flows into said third tank, and a pair of valves operated simultaneously by said electrical means for admitting air to said third tank and establishing a connection therefrom to the larger tank from which the liquefied material flowed to the other larger tank.

In witness whereof, I hereunto subscribe my name this 15 day of February, A. D. 1928.

CHESTER ARTHUR PURDY.
